UNITED STATES PATENT OFFICE.

WILLIAM E. WEBB, JR., OF LARCHMONT, NEW YORK.

NECKWEAR.

1,079,382.

Specification of Letters Patent.

Patented Nov. 25, 1913.

Application filed April 1, 1913. Serial No. 738,940.

To all whom it may concern:

Be it known that I, WILLIAM E. WEBB, Jr., a citizen of the United States, and resident of Larchmont, county of Westchester, State of New York, have invented certain new and useful Improvements in Neckwear, of which the following is a specification.

This invention relates to neckwear and it is adapted to various forms of ties, for instance, four-in-hands, ascots, etc.

The invention is especially designed for use on neckties made up of woven goods cut to the proper shape and folded to make the complete tie, the proper lining material, of course, being placed between the folds of the material.

The invention is particularly effective when applied to woven material that is cut and folded in such manner that the threads 20 thereof are on the bias, that is to say oblique to the longitudinal line of the tie.

The invention is especially designed for neckties designed to be worn with turned-down or double-fold collars which are so 25 largely worn at the present time.

As is well-known it is many times extremely difficult to adjust a necktie between the folds of a collar and frequently considerable strain is brought on the necktie in an 30 endeavor to shift it to its proper position for tying. It is also well-known that neckties, and particularly four-in-hand ties which are frequently formed of soft delicate silk material, are cut and folded so that a seam is 35 formed along the longitudinal line of the tie at the back or inner side thereof. The strain of adjusting a tie in the ordinary double-fold collar frequently breaks the delicate stitching of this seam, thereby rendering 40 the tie unsightly if not unusable; and the strain pulls the tie longitudinally, stretching the material and destroying the shape of the tie and giving to it a stretched and unsightly appearance. This difficulty is 45 particularly noticeable in ties made up of material with the threads running bias thereof.

The main object of this invention is to provide means for preventing the body of 50 the tie from being stretched longitudinally and laterally distorted, this same means also protecting the longitudinal seam on the inner face or back of the tie. This means also renders the neck-band part of the tie thin and flat so that it will readily slide between the folds of a turned down collar.

There are other objects and advantages of the invention which will appear hereinafter.

In the drawing, Figure 1 is a view of the back or inner side of a necktie of the four-in-hand type; Fig. 2 a view of the face or the outer side of the said tie; Fig. 3 a transverse sectional view thereof on the line III—III of Fig. 1; and Fig. 4 a similar view on the line IV—IV of Fig. 1.

Referring to the various parts by numerals, 1 designates the body portion of the necktie which is cut and folded so that a longitudinal seam 2 is formed along the center of the inner or under side thereof. This seam is preferably arranged along the center line of the tie, but, of course, that would be a matter of choice with the manufacturer. The main body of the tie is preferably cut so that the threads thereof are on the bias, or oblique to the longitudinal line of the tie. The tie is preferably lined for the greater portion of its length, as is usual in this type of neckwear, but with my invention this lining may or may not be used, according to the judgment of the manufacturer.

The material of the tie is so cut and folded that a long narrow neck-band portion 3 is formed, the ends 4 being open and considerably enlarged, as is usual in this type of neckwear. The portions 4^a between the neck-band portion of the tie and the open end portions constitute the knot forming portions of the tie. The edges of the material are stitched together for the major portion of the length of the tie, said edges at the open ends of the tie separating and diverging for a suitable distance inwardly from each end of the tie. The lining does not extend beyond either end of the stitched seam 2 so that it is not exposed at the open ends of the tie.

The neck-band and that portion of the body of the tie immediately adjacent thereto which constitute the knot forming portions of the tie, receives the greatest wear and the greatest pulling strain. To prevent this portion of the tie being stretched or pulled longitudinally I secure to the inner side or back thereof a long relatively inelastic, smooth-surfaced closely woven fabric band 5. This band is stitched along its longitudinal edges at 7 to the back fold only of the knot forming portions of the necktie material and covers the seam 2 for its entire length between the open ends of

the tie. The ends of this relatively inelastic band are firmly attached to the back of the tie by stitches passing transversely across the seam 2. At the neck-band portion of 5 the tie this relatively inelastic band is secured firmly in position by stitches 6 which pass through both folds of the band and the lining so that the neck-band portion is comparatively stiff and flat and will slide 10 freely through or between the folds of the collar. The lines of stitches 6 which pass through both folds or plies of the tie run longitudinally and transversely of the reinforcing band. 15 It is manifest that the inelastic reinforcing band will extend beyond the ends of the collar and throughout the knot forming portions of the tie, so that there will be no tendency for the ends of the band to become 20 detached from the necktie. It is also manifest that the strain of pulling up and tightening the knot in the tie will be largely brought on the reinforcing band or stay piece, and as the stay is inelastic it will prevent the elongation of the body of the tie. 25 This inelastic stay will also prevent the distortion of the body of the tie when the same is made of material cut and arranged to bring the threads on the bias. 30 It is manifest that the inelastic reinforcing stay may be applied to woven or knitted ties and that by properly securing said stay to the neck-band portion of the tie by lines 35 of stitches running longitudinally and transversely of the stay the neck-band por-

tion will be rendered flat and comparatively stiff so that it will slide freely through or between the folds of a turned down collar. I, therefore, do not wish to be limited in the application of my invention to neckties 40 made of a woven fabric cut and folded to the proper shape.

What I claim is:

A necktie formed of folded fabric and comprising a narrow neck-band portion, 45 knot forming portions at the ends of the neck-band portion, and enlarged ends, the edges of the folded fabric forming a longitudinal seam at the back of the tie, in combination with a longitudinally extending, 50 relatively inelastic smooth, flexible reinforcing piece covering the seam between the folded edges of the necktie fabric and protecting said seam throughout the entire length of the neck-band and the knot forming portions of the tie, lines of stitches along the longitudinal edges of the reinforcing piece connecting said piece to the back fold only of the tie throughout the 55 knot forming portions thereof, and lines of 60 stitches connecting said reinforcing piece to the back and face folds of the tie throughout the length of the neck-band portion thereof.

In testimony whereof I hereunto affix my 65 signature in the presence of two witnesses.

WILLIAM E. WEBB, JR.
